UNITED STATES PATENT OFFICE.

WILLIAM A. DOBLE, OF SAN FRANCISCO, CALIFORNIA, ASSIGNOR TO THE PELTON
WATER WHEEL COMPANY, OF SAN FRANCISCO, CALIFORNIA, A CORPORATION
OF CALIFORNIA.

PRESSURE-CONTROLLING APPARATUS.

1,127,968.

Specification of Letters Patent.

Patented Feb. 9, 1915.

Application filed June 2, 1913. Serial No. 771,310.

To all whom it may concern:

Be it known that I, WILLIAM A. DOBLE, a citizen of the United States, residing in San Francisco, county of San Francisco, 5 and State of California, have invented certain new and useful Improvements in Pressure-Controlling Apparatus, of which the following is a specification.

This invention relates to apparatus for 10 controlling the speed of water-wheels and more particularly to devices which vary the quantity of water delivered to the wheel and include an auxiliary discharge valve for the supply conduit, the auxiliary valve being 15 moved simultaneously with the main valve and in opposition thereto.

In devices of this class which have been heretofore used it has been the practice to 20 make the rate of change of the discharge opening through the auxiliary valve considerably less than the rate of change of the discharge opening through the main valve and this has been accomplished in the case 25 of impact water-wheels by making the area of the auxiliary valve or nozzle somewhat smaller than the main nozzle and in the case of a turbine the area of the auxiliary valve or nozzle somewhat smaller than the combined area of all of the gate openings into 30 the turbine wheel.

The principle upon which the constructions heretofore used have been made is that the auxiliary nozzle should be merely of sufficient size to prevent a dangerous rise in 35 pressure in the pipe-line due to a sudden closure of the main valve. The operation of these constructions is such that when the main valve or nozzle is closed suddenly by the governor, due to a reduction in the 40 power output of the unit controlled, the governor at the same time opens the auxiliary valve and as the latter has a somewhat smaller area than the main nozzle, the increase in the discharge of the auxiliary 45 valve will be less than the decrease in the discharge of the main nozzle and in consequence thereof there will be a rise in pressure in the pipe-line, although the parts are so designed that the rise in pressure will not 50 be dangerous. At the same time this rise in pressure will interfere with the regulation

of the unit because the increased pressure augments the spouting velocity of the water through the main nozzle so that, although the area of the main nozzle is reduced a certain amount, the quantity of water discharged through the nozzle will not be reduced in the same proportion. In addition to this the kinetic energy or power in the water is not reduced in the same proportion as the reduction in area on account of the increased discharge velocity of the water from the main nozzle and as a result there is an over-speeding of the unit.

The object, therefore, of my invention, is 65 to so construct the apparatus that these disadvantages of the constructions heretofore used will be obviated.

The principle upon which my invention is based is that of having the rate of change 70 of opening of the auxiliary discharge nozzle exceed the corresponding rates of change of the discharge opening of the main nozzle. As a result of having the changes in the area of the discharge opening of the 75 auxiliary valve or nozzle exceed the corresponding changes in the discharge opening of the main nozzle, when the load is thrown off the unit and the governor closes the main valve to a certain extent and at the same 80 time opens the auxiliary valve, the increase in the quantity of water discharged by the auxiliary valve will exceed the decrease in the quantity discharged by the main nozzle so that there will be, instead of a rise in 85 pressure in the pipe-line, a slight decrease in the pressure. This decrease in pressure also causes a decrease in the spouting velocity and energy of the water discharged by the main nozzle, thereby eliminating, to a 90 large extent, the over-speeding of the unit.

The application of my invention also has a beneficial effect on the regulation of the unit, when the load is suddenly increased. In the constructions heretofore used, an increase in the load on the unit would cause a sudden slowing down thereof and the governor would quickly open the main nozzle, and as it takes a certain appreciable time for the speed of the wheel to be brought 100 back to normal, the governor must necessarily over-open the main nozzle. This

causes the speed of the unit to increase above the normal desired speed, setting up a movement of the governor to quickly partially close the main nozzle and in making this closing movement the relief valve is opened. The effect of thus opening and closing the main and auxiliary nozzles is to produce a series of following waves in the pipe-line and these will set up corresponding variations in pressure and the spouting velocity of the water from the nozzle, which interfere with the proper regulation of the unit. When my invention is used, however, the rate of change in the discharge area of the auxiliary nozzle being greater than the corresponding change in the discharge area of the main nozzle, it momentarily discharges a larger quantity of water than the main nozzle and therefore absolutely eliminates the following waves and by eliminating these waves greatly improves the character of regulation and materially reduces the time required for the speed of the unit to become steady. By my invention, therefore, I not only avoid the possibility of overstraining the pipe-line and the interference with the speed regulation due to setting up pressure waves in the pipe-line, but I also improve the speed regulation by diminishing the maximum variations in speed from the normal and also the time required for bringing the unit to a steady speed.

The invention is illustrated in the accompanying drawings, in which, 35 Figure 1 is a side view of the invention as applied to an impact water-wheel, certain of the parts being shown in section; Fig. 2 is a bottom plan view of the auxiliary nozzle shown in Fig. 1; Fig. 3 is a view showing 40 the invention as applied to a turbine water-wheel, certain of the parts being shown in section.

Referring to Fig. 1, 10 indicates an impact wheel which is mounted on a suitable shaft (not shown), the wheel being provided with the usual buckets 11 and the casing 12. The wheel is supplied with water from the conduit 13 by means of the nozzle 14 controlled by the needle valve 15. The conduit 13 also has an auxiliary outlet 16 provided with a nozzle 17 and controlled by a needle valve 18, the valve 18 being preferably of larger size than the valve 15 so that equal movements of these valves will effect greater changes in the area of the discharge opening of the nozzle 17 than the nozzle 14. The valve 15 is provided with a stem 19 which extends through a suitable stuffing-box 20. The valve 18 is provided with a stem 21 which extends through the stuffing-box 22. The stuffing-box 20 is provided with laterally extending brackets 23 and 24 to which are connected the ends of the yoke 25. A rod 26 extends through a guide 27 in the

yoke 25 and is pivotally connected with the stem 19, as indicated at 28. A lever 29 is mounted on the pivot 30, carried by the yoke 25, and has its lower end pivotally connected with the piston-rod 31 which carries the piston 32 of the dash-pot 33. This dash-pot is pivotally connected with the stem 21 of the auxiliary valve, as indicated at 34. The stem 21 has secured thereto the yoke 35, the ends of which engage the springs 36 and 37, carried by the rods 38 and 39, secured to brackets 40 and 41 on the stuffing-box 22.

It will be seen from Fig. 2 that when the valve 18 is opened the springs 36 and 37 will be compressed and the rate of movement of the valve 18 regulated by the dash-pot 33. The upper end of the lever 29 is pivotally connected with the rod 26, as indicated at 42, and has its upper end pivotally connected with one end of the links 43, the other end of these links being pivotally connected with the arm 44, carried by the shaft 45 which may be mounted on the yoke 25 or any other suitable support. The shaft 45 also carries a segmental rack 46 which is engaged by a pinion 47 on the shaft 48. The shaft 48 is mounted in bearings on any suitable supports. An arm 49 carried by the shaft 48 is connected with the governor 50 by any suitable connection which is adapted to rock the arm in accordance with the changes in speed of the governor, the latter being driven by the wheel 10 by means of the belt 51. The rod 26 is provided on the opposite sides of the guide 27 with the buffer springs 52 and 53.

In the construction above described, the governor 50 will respond to changes in the speed of the wheel 10 in the well known manner and rock the arm 49 and thereby oscillate the pinion 47 and the rack 46. The motion of the rack 46 is transmitted to the arm 44 and through the links 43 to the lever 29 and by means of the connections between the lever 29 and the valves 15 and 18 these valves will be moved simultaneously and in opposite directions so that as the main valve 15 is opened the auxiliary valve 18 will be closed and vice versa. Owing to the fact that the auxiliary valve is larger than the main valve, it is obvious that the corresponding changes in the discharge area of the auxiliary valve will be greater than the changes in the discharge area of the main valve. I may also increase the difference in the rate of change of the openings in the valves by making the arm of the lever 29 which actuates valve 18 longer than the arm which actuates valve 15.

In Fig. 3 I have illustrated the invention as applied to a turbine water-wheel provided with the casing 54 having an inlet 55 and an auxiliary discharge outlet 56, the latter being controlled by a swinging gate

valve 57. The shaft 58 of the turbine is mounted in suitable bearings 59 and carries the water-wheel. The wheel is provided with the usual valves or gates which are controlled in any suitable manner, as by means of the shafts 60 which carry the arms 61. These arms 61 may be pivotally connected with a ring 62 which may be oscillated by means of the links 63 and 64 to simultaneously adjust the position of all of the gates. The links 63 and 64 may be connected with arms 65 and 66, carried by the shaft 67, which may be mounted in suitable bearings and is arranged to be oscillated by means of a governor in the same manner as the shaft 48, shown in Fig. 1. The shaft 67 also carries an arm 68 which is pivotally connected with the piston-rod 69 of the dash-pot device 70, the dash-pot being provided with suitable arms 71, which are pivotally connected with the gate valve 57.

It will be readily understood that by this construction the auxiliary valve 57 may be opened and closed simultaneously with the turbine gates and in opposition thereto and that the area of the valve 56 being larger than the combined area of all of the turbine gate openings, and the connecting link being suitably proportioned, the changes in the discharge through the auxiliary valve will be greater than the corresponding changes in the combined discharge of all of the turbine gates.

It will be understood that various changes may be made in the details of construction of the apparatus which will accomplish the object of this invention, which is broadly to provide apparatus for causing the main and auxiliary valves to be operated simultaneously and wherein the changes in the discharge opening of the auxiliary valve exceed the corresponding changes in the discharge opening of the main valve, and I therefore do not wish to be limited to the precise details of construction shown and described.

Having thus described my invention, what I claim is:—

1. In an apparatus of the class described, the combination of a motor, a main valve for controlling the supply of motive fluid to the motor, a supplemental valve, and means for simultaneously operating said valves, said parts being constructed and arranged to cause the changes in the area of the discharge opening of the supplemental valve to be opposite in phase to and to exceed the corresponding changes in the area of the discharge opening of the main valve.

2. In an apparatus of the class described, the combination of a motor, a motive fluid supply conduit, a main valve for controlling the supply of motive fluid to the motor, from said conduit, a supplemental valve

adapted to discharge the motive fluid from the conduit, a governor, and means operatively connecting said valves with the governor, said parts being constructed and arranged to cause the valves to be operated simultaneously and the changes in the area of the discharge opening of the supplemental valve to be opposite in phase to and to exceed the corresponding changes in the area of the discharge opening of the main valve.

3. In an apparatus of the class described, the combination of a motor, a motive fluid supply conduit, a main valve for controlling the supply of motive fluid to the motor, a supplemental valve for the conduit, and means for simultaneously operating said valves, said supplemental valve being larger than the main valve, and said means being arranged to cause the changes in the area of the discharge opening of the supplemental valve to be opposite in phase to and to exceed the corresponding changes in the discharge area of the main valve.

4. In an apparatus of the class described, the combination of a motor, a motive fluid supply conduit, a main valve for controlling the supply of motive fluid to the motor, a supplemental discharge valve for the conduit, a governor, and means operatively connecting said valves together and with the governor, said supplemental valve being larger than the main valve and said means being arranged to cause the valves to be operated simultaneously and the changes in the area of the discharge opening of the supplemental valve to be opposite in phase to and to exceed the corresponding changes in the discharge area of the main valve.

5. In an apparatus of the class described, the combination of an impact water wheel, a water supply conduit therefor, a main nozzle and valve for controlling the supply of motive fluid to the wheel, a supplemental nozzle and valve, a governor, a lever, means connecting said lever with said valves, and means operatively connecting said lever with the governor, said parts being constructed and arranged to cause the changes in the area of the discharge opening of the supplemental valve to be opposite in phase to and to exceed the corresponding changes in the area of the discharge opening of the main valve.

6. In an apparatus of the class described, the combination of an impact water wheel, a water supply conduit therefor, a main nozzle and valve for controlling the supply of motive fluid to the wheel, a supplemental nozzle and valve, a governor, and means operatively connecting said valves with the governor, said supplemental valve being larger than the main valve and said means being constructed and arranged to cause the

valves to be operated simultaneously and the changes in the area of the discharge opening of the supplemental valve to be opposite in phase to and to exceed the corresponding changes in the area of the discharge opening of the main valve.

In testimony whereof I affix my signature in presence of two witnesses.

WILLIAM A. DOBLE.
